UNITED STATES PATENT OFFICE.

SYLVESTER A. BAKER, OF SAN FRANCISCO, CALIFORNIA, ASSIGNOR TO BAKER SMITH COMPANY, INC., OF SAN FRANCISCO, CALIFORNIA, A CORPORATION OF CALIFORNIA.

DESIGN FOR A RADIO LOUD SPEAKER.

Application filed May 6, 1927. Serial No. 21,871. Term of patent 7 years.

To all whom it may concern:

Be it known that I, SYLVESTER A. BAKER, a citizen of the United States, residing at San Francisco, in the county of San Francisco and State of California, have invented a new, original, and ornamental Design for Radio Loud Speakers, of which the following is a specification, reference being had

to the accompanying drawing, forming a part thereof.

Figure 1 is a front elevation of my design. Figure 2 is an edge view thereof.

I claim:—

The ornamental design for a radio loud speaker substantially as shown.

SYLVESTER A. BAKER.
